HARTFORD CARPET COMPANY

Henry G. Thompson, Jr.

Dec 1715

Henry G. Thompson, of New York, N.Y.
Assignor to the
Hartford Carpet-Company.
Letter Patent No. 1715, Dated July 27, 1863.

The schedule referred to in these Letter Patent and making part of the same.

To all whom it may concern;

Des. 1715

Be it known that I, H. G. Thompson, of the City, County and State of New York, have invented or produced a new and original Design for a Pattern to be wrought into 2. ply, Ingrain and other carpeting in colors similar to those painted on the drawings accompanying this specification, or in other colors substituted in the place of those painted on the drawings herewith; and I do hereby declare that the drawings accompanying this specification, do give and convey to any one skilled in the Art of Carpet-weaving a more defined and thorough description of the nature of my invention, than it is in the power of language otherwise to convey, and as sufficient to enable any one skilled in the art of Carpet-weaving to use my invention.

What I claim as my invention and desire to secure by Letters Patent, is the configuration of the Design herewith annexed, when made by being wrought into 2. ply Ingrain or other carpeting, in the form indicated in the drawings accompanying this specification.
